(57) **CLAIM**

The ornamental design for a camera as shown and described.

DESCRIPTION

FIG. 1 is a top, front, right side perspective view of a camera showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The dashed broken lines in the drawings represent portions of the article and form no part of the claimed design. The dash-dot broken lines represent boundaries of the claimed design and form no part thereof. The dash-dot-dot broken lines in the drawings represent a symbolic break in the length of the camera and form no part of the claimed design. The appearance of any portion of the article beyond the break line forms no part of the claimed design.
